(57) **CLAIM**

The ornamental design for a security tool, as shown and described.

DESCRIPTION

FIG. 1 is a front perspective view of a security tool showing my new design.

FIG. 2 is a front view of the security tool shown in FIG. 1. FIG. 3 is a rear view of the security tool of FIG. 1.

FIG. 4 is a left side view of the security tool of FIG. 1.

FIG. 5 is a right side view of the security tool of FIG. 1.

FIG. 6 is a top plan view of the security tool of FIG. 1.

FIG. 7 is a bottom view of the security tool of FIG. 1; and, FIG. 8 is a front perspective view of a mirror image of the security tool shown in FIG. 1.

The broken lines are included for the purpose of illustrating portions of the security tool that are not considered part of the claimed design.

1 Claim, 8 Drawing Sheets
